Courtaulds Limited, London, England, a British
company

Application December 27, 1951, Serial No. 263,568
In Great Britain November 5, 1948

2 Claims. (Cl. 57—76)

1

This invention relates to rayon spinning machines and is particularly concerned with the traverse mechanism by which the funnel feeding the extruded filaments into a rotating spinning box is traversed through the action of followers on a cam. This application is a continuation-in-part application of our application, Serial No. 120,904, filed October 12, 1949, now abandoned.

In accordance with conventional practice the curve of the cam is a so-called "true cardiac curve" (in fact a portion of a spiral of Archimedes combined with its mirror image), rounded at the tip and root for some 3°. This curve gives a steady traverse for the thread guide and the rounding over an angle of some 3° is not sufficient to interrupt in any material way the steady traversing action so that a cake with substantially cylindrical and parallel surfaces is obtained. In practice it is usual to make the height of the spinning box slightly greater than the stroke of the thread guide, for example, with a stroke of 4.49 inches the height of the box is normally 4.6 inches. With existing apparatus it has now been found that there is a maximum permissible speed at about 32 beats per minute and above this speed there is excessive vibration of the thread guides which results in faulty cakes. One cause is the fact that the acceleration given to the cam-follower at speeds above 32 beats per minute exceeds the acceleration due to gravity (g) at the tip and at the root of the cam.

In standard pot spinning machines, two banks of funnels are reciprocated by two cams arranged at the ends of the banks. Each cam has a follower, and the two followers are arranged on a traverse bar 30 (in Fig. 4 of this application). In practice one cam will wear more than the other, so that one cam follower will not in practice completely follow the contour of its cam, but will be influenced by the other follower to leave the surface of the cam and crashes back on to it after a short aerial path. The shock is transmitted to the traverse rail which thus vibrates with its own natural frequency.

The specification of co-pending application, Serial No. 255,388, filed November 8, 1951 (now Patent No. 2,633,693), which is a continuation-in-part of application, Serial No. 54,626, filed October 15, 1948, and now abandoned, describes and claims a rayon centrifugal spinning machine comprising a spinning box, a thread guide for feeding filaments to the spinning box and a cam-follower for traversing the thread guide axially of the spinning box in which machine there is provided the combination of a cam activating

2

said cam follower, said cam being rounded off at the tip and the root over angles of at least 10° (preferably 15°) whereby the stroke of the guide has an appreciable dwell at each end and filaments are accumulated at the top and bottom of the box, and means for adjusting the height of the box with respect to the stroke of the cam so that the stroke of the guide is substantially shorter than the height of the spinning box in such degree that automatic spreading out of the accumulated filaments occurs and a cake having inside and outside surfaces substantially cylindrical and parallel is obtained. The spinning machine described in the said specification permits the use of speeds of the order of 48 beats per minute.

It is the object of the present invention to provide improved spinning machines capable of operating at even higher speeds.

According to the present invention a rayon spinning machine comprising a spinning box, a funnel for feeding filaments to the spinning box and a cam follower for traversing the funnel axially of the spinning box is provided with the combination of a funnel for feeding extruded filaments to said box and having its feeding edge indented, a cam activating said cam follower, said cam being rounded off at the tip and root over angles of from about 14° to about 30°, whereby the stroke of the guide has an appreciable dwell at each end and filaments are accumulated at the top and bottom of the box, and means for adjusting the height of the box with respect to the stroke of the cam so that the stroke of the guide is substantially shorter than the height of the spinning box; the shortened stroke of the guide and the corrugations of the funnel combining to cause automatic spreading out of the accumulated filaments and the formation of a cake having inside and outside surfaces substantially cylindrical and parallel.

The use of a funnel having an undulating or indented edge in accordance with the invention in general permits the production of cakes with substantially parallel sides by the use of cams which are rounded off over angles of 14° to 30°. Cams rounded off over angles of from 22½° to 30° have been used satisfactorily in machines according to the invention operating at spinning speeds of the order of 60 to 70 beats per minute or even higher.

The cams employed in the present invention are preferably so rounded off that the modified cam surfaces follow an arc of a circle in such a way that its tangents at the points where round-

ing begins are coincident with the tangents to the true cardiac curve; by so rounding off, the modified cam surfaces at the tip and the root to all intents and purposes follow the curve of a constant acceleration cam so that the cam used is in effect a combination of a constant velocity cam and a constant acceleration cam, the latter forming the tip and root of the composite cam, preferably over angles of the order of $22\frac{1}{2}^\circ$ to 30° . In an alternative form of cam, the tip of the cam is rounded off over an arc as described above but the root of the cam is made flat.

With the rayon spinning machines according to the invention, it is important that the traverse-stroke of the funnel should be sufficiently shorter than the height of the box to permit the automatic spreading out of the accumulated filaments in the box to give a cake of uniform thickness. The adjustment of the height of the box relative to the stroke of the thread guide may conveniently be made as described in application, Serial No. 255,388 by raising the bottom of the funnel (the normal thread guide employed) from the floor of the box to the required extent for example by holding the funnel in a ring held by a screwed bush which can be screwed upwardly or downwardly so that the bottom of the funnel is correspondingly moved upwardly or downwardly, and providing the box with a lid having a recess of substantially increased depth. Thus with a series of lids each with a different depth below the recess, provision may be made so that different types of cakes can be collected with a single box. The difference between the height of the box and the stroke of the thread guide is preferably varied according to the denier of the thread being spun, the higher the denier the greater the difference. This difference may be ascertained by simple tests by varying the position of the bottom of the funnel and using lids of different thicknesses.

Funnels having undulating or indented edges suitable for use in the present invention are described in United States Patent No. 2,100,595.

The invention is illustrated by way of examples in the accompanying diagrammatic drawings in which:

Figure 1 is a plan view of one form of cam suitable for use in the present invention, the cam being rounded off over angles of 30° .

Figure 2 is a vertical section of a funnel and a centrifugal spinning box,

Figure 3 is a plan view of a further form of cam which is rounded off over angles of $22\frac{1}{2}^\circ$.

Figure 4 is a diagrammatic view on a reduced scale of a double-sided spinning machine in accordance with the invention comprising a rounded cam, a cam follower, a traverse bar and two funnels with undulating ends, and

Figures 5 and 6 show lids having recesses of different depths to give the necessary adjustment of the height of the box X.

Figure 1 shows a cam 1 which apart from the tip 2 and the root 3 follows the so-called "true cardiac curve." The tip 2 and root 3 are both rounded off over an angle α subtended at the centre 0 of the cam 1, α as shown being 30° . Chain lines 4 and 5 show the tip and root respectively of a true cardiac curve and illustrate the effect of rounding off the cam in accordance with the invention.

Referring to Figures 2 and 4, a reciprocating funnel 6 is used to lay a thread 7 into a centrifugal spinning box 8 to form a cake 9. The funnel 6 has an undulating end 10, which lays 75

the thread 7 in the box 8, a stem part 11 and a cone-shaped part 12 which rests on a metal ring 13 in the top of a bush 14. Bush 14 screws into a support 15 which is reciprocated by a bar 16 which, in accordance with standard practice is secured to a follower 23 which runs in the groove of the cam 1. The follower 23 slides vertically on guides 24. Adjustment of the position of the funnel at the bottom of the stroke is obtained by screwing the bush 14 upwardly or downwardly as the case may be. The spinning box 8 is provided with a circumferential lip 18 and a lid 17 with a recess 19 of appreciable depth and a central hole 20 for passage of the funnel 6. In accordance with the present invention the height of the box (X) is made longer than the length (Y) of the traverse stroke of the funnel 6 so that the thread 7 when formed into the cake 9, automatically spreads out to form a cake having substantially cylindrical and parallel inside and outside surfaces. Other lids 17, having recesses 19' and 19'' of different thicknesses are illustrated in Figures 5 and 6. In order to compensate for the effects of gravity at the ends of the stroke, the difference between the end points of X and Y at the top of the box is made less than at the end points of X and Y at the bottom of the box.

Figure 3 shows a cam 25 which has been rounded off at the tip 26 and the root 27 over an angle β of $22\frac{1}{2}^\circ$. The normal tip and root of a "true cardiac curve" are shown in chain lines at 28 and 29 respectively.

The invention is illustrated by the following examples in which the percentages are by weight. In Example 1 a cam having its tip and root rounded off over 30° as shown in Figure 1 was used with a spinning box assembly and machine as shown in Figures 2 and 4; in Example 2 a cam having its root and tip rounded off over $22\frac{1}{2}^\circ$ as shown in Figure 3 was used, also with the spinning box assembly and machine shown in Figures 2 and 4.

Example 1

Viscose containing 8 per cent of cellulose and 6.5 per cent of caustic soda, aged to a salt point of 6.0, was extruded through a jet containing 27 holes, each five thousandths of an inch in diameter, into a coagulant bath at 50° centigrade containing 10 per cent of sulphuric acid, 18 per cent of sodium sulphate and 1 per cent of zinc sulphate, to produce a 150 denier thread. The thread so formed was withdrawn from the bath at a speed of 85 metres per minutes and was passed round a godet driven at such a speed that the thread was stretched 25 per cent. From the godet the thread was passed at a speed of 106.25 metres per minute to a centrifugal box 8 rotating at 7,000 revolutions per minute. The thread was led into the box by means of a funnel 6 which had an undulating end 10 containing 8 undulations each of 2 mm. depth and which was traversed through a cam-follower 23 operated by the cam 1 having both its root and tip rounded off over angles of 30° as shown in Figure 1. The rate of reciprocation of the funnel 6 was 70 beats per minute. The length of the traverse, corresponding to Y in the drawing, was 4.37 inches, the height of the box, corresponding to X in the drawing, was 4.72 inches and the funnel was set so that at the bottom of its stroke, the corrugated end 10 was within 0.24 of an inch of the bottom of the box. Despite the fact that the cam 1 was operated at about twice the speed normally employed hitherto, the traverse was smooth in

5

action and did not give rise to excessive vibration. The inside and outside surfaces of the cake of thread obtained were cylindrical and parallel and the cake was readily penetrated by the customary processing liquids such as for example washing liquids.

Example 2

Viscose containing 8 per cent of cellulose and 6.5 per cent of caustic soda, aged to a salt point of 5.8, was extruded through a jet containing 27 holes, each five thousandths of an inch in diameter, into a coagulant bath at 60° centigrade containing 9.5 per cent of sulphuric acid, 20 per cent of sodium sulphate and 1.5 per cent of zinc sulphate, to produce a 150 denier thread. The thread so formed was withdrawn from the bath at a speed of 95 metres per minute and was passed round a godet driven at such a speed that the thread was stretched 25 per cent. From the godet the thread was passed at a speed of 118.75 metres per minute to a centrifugal box rotating at 7,000 revolutions per minute. The thread was led into the box by means of a funnel 6 which had an undulating end containing 8 undulations each of 2 mm. depth and which was traversed through a cam-follower operated by a cam 25 having both its root and tip rounded off over angles of $22\frac{1}{2}^\circ$ as shown in Figure 3. The rate of reciprocation of the funnel 6 was 65 beats per minute. The length of the traverse (Y) was 4.37 inches, the height of the box (X) was 4.71 inches and the funnel was set so that at the bottom of its stroke, the corrugated end 10 was within 0.23 of an inch of the bottom of the box. Despite the fact that the cam 25 was operated at about twice the speed normally employed hitherto, the traverse was smooth in action and did not give rise to excessive vibration. The inside and outside surfaces of the cake of thread obtained were cylindrical and parallel and the cake was readily penetrated by the customary processing liquids such as for example washing liquids.

What we claim is:

1. In a rayon centrifugal spinning machine

6

comprising a spinning box, a funnel for feeding filaments to the spinning box and a cam-follower for traversing the funnel axially of the spinning box, the combination of a funnel for feeding extruded filaments to said box and having its feeding edge indented, a cam activating said cam-follower, said cam having the shape of a true cardiac curve except for the tip and the root, said cam being rounded off at the tip and root over angles of from about 14° to about 30° , whereby the stroke of the guide has an appreciable dwell at each end and filaments are accumulated at the top and bottom of the box, and means for adjusting the height of the box with respect to the stroke of the cam so that the stroke of the guide is substantially shorter than the height of the spinning box; the shortened stroke of the guide and indentation of the funnel combining to cause automatic spreading out of the accumulated filaments and the formation of a cake having inside and outside surfaces substantially cylindrical and parallel.

2. A machine as claimed in claim 1 wherein the cam is rounded off at the tip and root over angles of from about $22\frac{1}{2}^\circ$ to 30° .

LESLIE ROSE,
ERIC JOHN WHYTE.
